[57] CLAIM

The ornamental design for a sweater or similar article, substantially as shown and described.

DESCRIPTION

FIG. 1 is a front perspective view of a sweater or similar article showing my new design;
FIG. 2 is a rear perspective view; and
FIG. 3 is a view similar to FIG. 1 with the arms moved to better show the body of the sweater.
The waistband is of a dark, contrasting tone and the cuffs are ribbed.
